UNITED STATES PATENT OFFICE.

DAVID C. KLAUSMEYER, OF CINCINNATI, OHIO, ASSIGNOR TO THE CINCINNATI BICKFORD TOOL COMPANY, OF OAKLEY, CINCINNATI, OHIO, A CORPORATION OF OHIO.

STRAIN REVERTER.

1,412,806.

Specification of Letters Patent. Patented Apr. 11, 1922.

Application filed September 9, 1920. Serial No. 409,143.

To all whom it may concern:

Be it known that I, DAVID C. KLAUSMEYER, a citizen of the United States, and residing at Cincinnati, in the county of Hamilton 5 and State of Ohio, have invented a new and Improved Strain Reverter, of which the following specification is a full disclosure.

This invention deals with machine-tools and it proposes an instrumentality for 10 eliminating or reducing distortions or movements of frame-elements in consequence of the variable resistance-effects of a tool in cutting operation.

In the development of machine-tools, two 15 primary conditions are encountered; first, the inherent resiliency of the frame elements and, second, the back-lash inherent in the sliding joints employed for the purpose of securing adjustment.

20 The ultimate desideratum is, of course, to secure an absolute immobility in the adjustments of the tool relative to the work and to maintain this immobility throughout the tooling operation. The back pressures resulting from the tooling operation 25 operate to flex the frame-elements in proportion to their resiliency, and it has been the universal practice to combat this tendency to yield by increasing the dimensions of the frame-elements, by peculiarly 30 proportioning them, and by resorting to various reinforcements in their design. In the early days, no provision, beyond a more precise interfitting of the slideways, was 35 made to correct the irregularities resulting from the back-lash (which was then regarded as unavoidable) but, subsequently, special clamping devices were incorporated in the machine whereby the adjustable elements 40 could be strongly clamped on their bearing ways after the adjustment in position of the element had been made.

During subsequent developments, the designing of machine-tools has been proceeded 45 with on the general assumption that, from the beginning to the end of the cutting operation, the work would oppose a substantially unvariable and continuous resistance to the tool; although it was recognized that this is not actually the case, but 50 that, on the contrary, the pressure required to start the tool into the work will be materially different from that thereafter required to feed it during the normal cutting period.

55 No means has heretofore been proposed, in

the designing of machine-tools, for offsetting or compensating for this variation, and it has been considered as an unavoidable evil. In the case of certain tools, notably drills, it has for long been observed that a 60 pressure, materially greater than that required for normal cutting, must be put upon the drill to cause it to initially penetrate the surface or skin of the metal. Likewise, it was noted that, when the drill cut through 65 the remote side of the work, its advance was not only unopposed but it actually manifested a decided tendency to rifle the opening, and this rifling thereupon exercised a pronounced pull on the drill. 70

These effects are especially observable if the machine-tool be so designed, as in the case of so-called "radial drills," that the drilling-pressures tend to deflect a frame-element in a direction contrary to the deflection 75 caused by its own gravity. For example, a so-called radial-drill presents a column; vertically along which slides an overhanging arm that protrudes for a considerable distance transversely to the 80 column. This arm is provided with a suitable mechanism for holding and rotating a drill which is arranged to project downwardly so as to pierce the work affixed to an underlying bed. 85

However perfectly the arm may be fitted to the column, there must always be a certain amount of back-lash so long as the union admits of relative adjustment. The weight of the arm takes up the back-lash 90 between the arm and the column in the downward direction, but obviously cannot take it up in the upward direction. Consequently, any force urged upwardly against the overhanging arm and which in degree 95 exceeds the weight of the arm assembly, will operate to lift the arm and swing it upwardly about its bearing on the column to the extent afforded by whatever amount of back-lash may exist. This may happen 100 when a large-sized drill is being urged against the surface-skin of a casting by the mechanism for feeding the drill. The arm may be actually lifted, so to speak, against its own weight so that it swings upwardly 105 in an arc, the center of which is located at its bearing on the column. This shifts the drill-point laterally, to a proportionate extent, with the effect that the accuracy of the work is impaired. At the same time, 110

this naturally introduces opportunities for vibration.

An attempt has been made, heretofore, to eliminate all such yields by resorting to 5 clamps adapted to bind the bearing-surfaces tightly together after the parts have been brought into their predetermined positions of adjustment with the idea of entirely 10 eliminating every trace of back-lash. As a result of much experience, it has been found, that, while these clamps greatly improve the 15 operation of the mechanism, nevertheless the correction is not absolute and that there still exists a great deal of chatter and vibration 20 which is becoming more and more manifest as machine-tools are required to perform the increasingly heavy work of modern developments. It is debatable whether, in an absolute sense, even the most powerful clamps 25 will actually eliminate all back-lash or prevent minute yields under the conditions obtained in actual practice.

But, irrespective of yields attributable to loose slideways, in consequence of the above-described properties of a drill, alternate and variable strains are imposed upon the various frame-elements of the machine. First, there exists an abnormal pressure straining and unduly deflecting the tool-support and 30 the work-support apart. This occurs during the initial penetrating or starting period of the drill. Second, during the normal working-period the supports are urged apart to a less pronounced degree by the normal 35 drilling pressures. Lastly, the supports are pulled together, i. e., deflecting in a contrary direction to a limited degree by the rifling effect above mentioned. Obviously, all of this interferes with the ultimate precision 40 of the machine-tool and it correspondingly stimulates the tendency of the tool to chatter and, to a certain extent, impairs the quality or accuracy of the work.

This invention undertakes to correct this 45 difficulty in an entirely different way from anything heretofore conceived, instead of depending entirely upon the use of clamps to prevent chatter, an auxiliary take-up contrivance is proposed; it being adapted in 50 certain cases to serve, not so much for the purpose of taking-up back-lash, as to take-up what may be regarded as the excess resiliency in the frame-elements of the machine-tool. As a result of special observations 55 made in the course of developing this invention, it has been noted that no matter how heavily the parts may be constructed, within reasonable limits, or however completely they may be reinforced, or however 60 thoroughly they may be clamped at their bearing surfaces, they still admit of a considerable amount of "give" owing to the normal excess elasticity or resiliency of the metal. In other words, the metal functions 65 in a manner analogous to a tapered spring

and it will yield in an inverse (by reason of its shape) proportion to the pressure imposed upon it. The conclusion was finally reached that, instead of attempting to prevent deflection solely by means of conventional reinforcing ribs in the frame-elements, or by extra braces, or bearing clamps, the deflection producible by the tool, should be anticipated, so to speak, through the agency of a special instrumentality capable 70 of instituting an initial back-pressure of the same nature, and more or less of the same extent, as that which could be produced by the tool; thereby leaving no substantial amount of residual deflection at the disposal 80 of the tool. The ultimate effect of this device is, accordingly, to increase the stiffness of the machine, taken as a whole, by flexing it to an extent beyond which the maximum thrusts of the tool are incapable of exercising any objectionable influence.

Other objects and advantages will be in part indicated in the following description and in part rendered apparent therefrom in connection with the annexed drawings. 90

To enable others skilled in the art to so fully apprehend the underlying features hereof that they may embody the same in the various ways contemplated by this invention, drawings depicting a preferred typical construction have been annexed as a part of this disclosure, and in such drawings like characters of reference denote corresponding parts throughout all the views, of which:—

Fig. 1 is a front elevation, partly in section, of a radial drill embodying this invention. Fig. 2 is a fragmentary side elevation of a pneumatic system exemplifying one of the many ways of applying this invention. 10 Fig. 3 is a plan, partly in section, along line 3—3 of Fig. 2. Fig. 4 is a section through 4—4 of Fig. 2 illustrating a type of valve which may be used if desired. Fig. 5 is a detail of an adjustable lever control for 11 transmitting appropriate pressures to the thrust rod.

Referring to the drawings, A and B represent elements of a machine tool; the one carrying an appropriately mounted cutting tool, and the other being adapted to support the work. For purposes of adjustment, these elements are connected by a series of other elements providing various relative movements. This invention is applied more directly to one or the other of elements A and B for the purpose of stabilizing their relationship as explained in the foregoing, and this invention is so arranged as to render it applicable within the general range of adjustability between the elements A and B. 12

The machine tool selected for the purpose of representing this invention, here assumes the form of a radial drill consisting of a base C providing a table or surface B suitable for 13

supporting the work. A post D extends upwardly from the base C and pivotally supports a sleeve E; this sleeve, in turn, carrying the arm F which is vertically slideable thereon. The elevation and depression of the arm is effected by a screw G driven by a suitable transmission H. The arm F is provided with slideways I on which rests the saddle or head A; thereby affording lateral 10 adjustments of the cutter support J journaled appropriately in the head A and suitably power driven. It is unnecessary to explain the details of the foregoing arrangement inasmuch as, for the purposes of this 15 case, they may be regarded as purely conventional.

Fig. 1 shows a number of plates K resting on the table B with the cutting tool L (here in the form of a drill) about to effect a tooling operation. This drill, as it successively enters and passes through the respective plates K, will be subjected to great variations in duty. In fact, the drilling of a pile of plates of sheet-metal, is ordinarily a very 25 troublesome operation. By means of this invention, the drilling may be effected easily and accurately, and this instance has been selected as best representing a typical embodiment of invention.

30 Mounted in head A is a thrust element M which admits of being moved against the work support B or against any intervening portion of the work resting thereon. By causing the thrust member M to press 35 directly against the work K, a two-fold function is performed; the thrust not only being reverted as explained in the foregoing, but the work being additionally clamped or secured against displacement and especially 40 against any tendency to clamp the drill. Various arrangements may be resorted to within the sphere of this invention, for the purpose of exercising a thrust between the member M and the elements A and B. In 45 the example herein illustrated, the thrust member M is longitudinally movable in the bearing 1 and has its upper end portion provided with screw-threads 2. An internally threaded collar 3 circumscribes the threaded 50 portion 2 and this collar is split and provided with a clamping bolt 4. By loosening the bolt 4, and rotating the rod M, it may be initially adjusted into proximity with the work K after the drill L has been brought 55 approximately into position. The bolt 4, is then tightened and the rod M may then be given an additional movement sufficient to produce the result described. While this additional movement may be effected by screw- 60 ing up the rod M before tightening the bolt 4, it is preferably effected by a resilient instrumentality such, for example, as a pneumatic system. To this end, the collar 3 is provided with lateral openings 5 which receive pivot pins 6 carried by one end of a

bifurcated lever which, by means of pivot 8, is mounted in head A. The other end of this lever 7 likewise provides pivot pins 9 which engage suitable recesses 10 in the lower head 11 of a plunger 12 actuated by a piston 70 reciprocating within a suitable chamber 14 attached to the head A. A hand valve N is secured at some accessible point on the head A and admits of being manipulated to actuate the thrust rod M through the linkage 75 above described. This valve may assume any conventional form; it being here shown as a 4-way valve. By turning the handle O into the position shown in full lines in Fig. 1, air under pressure will flow from a suitable 80 source through the inlet pipe 15, thence through the channel 16 (see Fig. 4) into the pipe 17 and then against the under side of the piston 13. This will raise the piston and depress the thrust rod M and revert the strains. 85 When the inlet pipe 15 is connected with the pipe 17, the upper portion of the chamber will, through the pipe 18, be simultaneously connected directly with the outlet 19 so that there will be no back pressure. Conversely, 90 by moving handle O into the dotted position, shown by Fig. 1, the intervening rod M will be lifted and rendered inactive.

It will thus be perceived that the objects of this invention have been shown in a simple 95 yet effective manner and by means of an instrumentality applicable in many different ways to various types of machine tools.

Without further analysis, the foregoing will so fully reveal the gist of this invention 100 that others can, by applying current knowledge, readily adapt it for various utilizations without omitting certain features that, from the standpoint of the prior art, fairly constitute essential characteristics of the generic 105 or specific aspects of this invention, and therefore such adaptations should be and are intended to be comprehended within the meaning and range of equivalency of the following claims.

Having thus revealed this invention, I claim as new the following combinations of elements or equivalents thereof, and desire to secure the same by Letters Patent of the United States:

115 1. A machine-tool combining a bed adapted to support an article to be machined; a tool-supporting member overlying said bed and normally urged by gravity towards the same; a frame element located at a side of said bed to carry said member; mechanism for elevating said frame-element; and independent adjustable means acting counter to the pull of gravity to urge said member away from said bed against the restriction 120 of said frame-element, said means being located closely adjacent said tool supporting member.

125 2. A machine-tool combining a bed adapted to support the work to be tooled; a frame- 130

- element adjacent said bed; a tool-supporting member mounted on said frame-element; and means adjustably intervening between said member and the work supported by said bed to urge the same apart so as to press said work onto its support and simultaneously counter-vail the strains in said member, said means being located closely adjacent said tool supporting member.
10. 3. A machine-tool combining a bed; a frame-element adjacent said bed; a tool-supporting member mounted on said frame-element and extending over said bed; and means for exerting an upward adjustable strain on said member, said means being located closely adjacent said tool supporting member.
15. 4. A machine-tool combining a bed; a frame-element adjacent said bed; a tool-supporting member mounted on said frame-element and extending over said bed; and means for exerting an upward adjustable pressure against said member to reduce its gravitational deflection, said means being located closely adjacent said tool supporting member.
20. 5. A machine-tool combining a bed; a frame-element adjacent said bed; a tool-supporting member mounted on said frame-element and extending over said bed; and a thrust-rod intervening between said bed and arm and adjustable to flex said arm in opposition to the pull of gravity, said means being located closely adjacent said tool supporting member.
25. 6. A machine-tool combining an upright frame-element; a tool-supporting member slidably mounted on it; means for retaining said member in a predetermined position on said frame-element; a work-support; auxiliary means; and a manually controlled instrumentality for so regulating the position of said auxiliary means with relation mutually to both said work-support and said tool-supporting member as to impose on said member strains of the same nature as those imposed on it by the tool when at work, said means being located closely adjacent said tool supporting member.
30. 7. A machine-tool combining an upright frame-element; a tool-supporting member slidably mounted on it; means for retaining said member in a predetermined position on said frame element; a work-support; an auxiliary support mounted on said member and adapted to be retracted during the preliminary adjustments in the position of said member, and adapted to be protruded towards the work-support to steady said member during tooling periods; and means for forcibly protruding said auxiliary support to create reverse strains in said frame-element.
35. 8. A machine-tool combining an upright frame-element; a tool-supporting member slidably mounted on it; means for retaining said member in a predetermined position on said frame-element; a work-support; a plunger supported by said member and vertically adjustable against the work on its support; and a plunger-actuator adapted to thrust said plunger forcibly against said work.
9. A machine-tool combining an upright frame-element; a tool-supporting member slidably mounted on it; means for retaining said member in a predetermined position on said frame-element; a work-support; and a forcibly urged compression means intervening between said member and the work-support adapted to bear directly against the work to exert pressure between said member and said work.
10. A machine-tool combining a tool-support; a work-support extending parallel therewith and spaced apart therefrom; a stationary frame-element located at the ends of said supports and extending transversely thereto, one of said supports being adjustable along said frame-element; means embodying a compression element carried by one of said supports; and a device for adjustably determining the operative effect of said compression element whereby it will impose a limited repellent strain between said supports.
15. 11. A machine-tool combining a tool-support; a work-support extending parallel therewith and spaced apart therefrom; a stationary frame-element located at the ends of said supports and extending transversely thereto, one of said supports being adjustable along said frame-element; a head slidably mounted on one of said supports; and means embodying a compression element intervening between said head and the other support for straining said supports apart to a limited degree.
20. 12. A machine-tool combining a tool-support; a work-support extending parallel therewith and spaced apart therefrom; a stationary frame-element located at the ends of said supports and extending transversely thereto, one of said supports being adjustable along said frame-element; a head slidably mounted on one of said supports; and an auxiliary thrust member slidably mounted on said head and adapted to be urged towards the opposed support to strain said supports apart to a limited degree.
25. 13. A machine-tool combining a tool-support; a work-support extending parallel therewith and spaced apart therefrom; a stationary frame-element located at the ends of said supports and extending transversely thereto, one of said supports being adjustable along said frame-element; a head slidably mounted on one of said supports; a thrust plunger slidably mounted in said head and adapted to be protruded therefrom; and

- means for restraining said plunger against retreat.
14. A machine-tool combining a bed adapted to support an article to be machined; a tool-supporting member overlying said bed and normally urged by gravity towards the same; a frame-element located at a side of said bed to carry said member; and resilient compression means acting counter to the pull of gravity to urge said member away from said bed against the restriction of said frame-element.
15. A machine-tool combining a bed; a frame-element adjacent said bed; a tool-supporting member mounted on said frame-element and extending over said bed; and resilient compression means intervening between said bed and member to urge the same apart.
16. A machine-tool combining a bed; a frame-element adjacent said bed; a tool-supporting member mounted on said frame-element and extending over said bed; and pneumatically actuated means for exerting an elastic upward strain on said member.
17. A machine-tool combining a bed; a frame-element adjacent said bed; a tool-supporting member mounted on said frame-element and extending over said bed; and means actuated by a piston and air-cylinder for exerting an upward pressure against said tool-supporting member, said means being adjustably connected to said piston.
18. A machine-tool combining a bed; a frame-element adjacent said bed; a tool-supporting member mounted on said frame-element and extending over said bed; and an air-actuated thrust-rod intervening between said bed and arm and adjustable to flex said arm in opposition to the pull of gravity.
19. A machine-tool combining an upright frame-element; a tool-supporting member slidably mounted on it; means for retaining said member in a predetermined position on said frame-element; a work-support; auxiliary means for initially imposing on said member strains of the same nature as those imposed on it by the tool when at work; and a pneumatic system for controlling said means.
20. A machine-tool combining an upright frame-element; a tool-supporting member slidably mounted on it; means for retaining said member in a predetermined position on said frame-element; a work-support; an auxiliary support slidably mounted on said member; and pneumatic means adapted to retract said support during the preliminary adjustments in the position of said member, and adapted to protrude it towards the work-support to steady said member during tooling periods.
21. A machine-tool combining an upright frame-element; a tool-supporting member slidably mounted on it; means for retaining said member in a predetermined position on said frame-element; a work-support, a plunger supported by said member and vertically adjustable thereto; and a valve-controlled pneumatic system for actuating said plunger.
22. A machine-tool combining an upright frame-element; a tool-supporting member slidably mounted on it; means for retaining said member in a predetermined position on said frame-element; a work-support; means intervening between said member and the work-support adapted to bear directly against the work to exert pressure between said member and said work; an air-system for actuating said means; and a handle carried by said member for controlling said air-system.

In witness whereof, I hereunto subscribe my name, as attested by the two subscribing witnesses.

DAVID C. KLAUSMEYER.
